UNITED STATES PATENT OFFICE.

EUGENE T. KIEFFER AND WILLIAM B. STEVENSON, OF PHILADELPHIA, PENNSYLVANIA, ASSIGNORS TO VICTOR TALKING MACHINE COMPANY, A CORPORATION OF NEW JERSEY.

DESIGN FOR A CABINET FOR TALKING MACHINES.

Application filed November 11, 1922. Serial No. 4,255. Term of patent 14 years.

To all whom it may concern:

Be it known that we, EUGENE T. KIEFFER and WILLIAM B. STEVENSON, both citizens of the United States, and residents of the city of Philadelphia, county of Philadelphia, and State of Pennsylvania, have invented a new, original, and ornamental Design for Cabinets for Talking Machines, of which the following is a specification, reference being had to the accompanying drawing, forming a part thereof.

In the drawing is shown a perspective view of a cabinet embodying our new, original and ornamental design.

We claim:

The ornamental design for a cabinet for talking machines, as shown.

EUGENE T. KIEFFER.
WILLIAM B. STEVENSON.
